OPERATING ROOM LAMP

Hermann Gunther, Hanau (Main), Germany, assignor to Quarzlampe Gesellschaft m.b.H., Hanau (Main), Germany

Filed Apr. 30, 1957, Ser. No. 655,985

2 Claims. (Cl. 240—1.4)

The present invention relates to an operating room lamp, more particularly, to such a lamp which may be readily adjusted around a plurality of different axes by manipulation of controls on the lamp which are located outside of the region where the operation is being performed.

It is, therefore, the principal object of this invention to provide an improved adjustable operating room lamp.

It is another object of this invention to provide an operating room lamp which overcomes the disadvantages of the previously known operating room lamps whose position could only be adjusted by manipulating of the lamp directly above the area in which the operation was being performed.

It is a further object of this invention to provide an operating room lamp having a compensated drive for adjusting the lamp around a horizontal axis which requires very little force to be exerted by personnel adjusting the position of the lamp.

It is an additional object of this invention to provide an operating room lamp wherein the position of the lamp is adjusted on that part of the frame which is remote and opposite to the actual lamp.

It is still another object of this invention to provide an operating room lamp whose position is capable of being finely adjusted.

It is still a further object of this invention to provide an operating room lamp wherein the horizontally adjustable frame supporting the lamp is maintained in a horizontal position by a compensating spring.

Other objects and advantages of this invention will become apparent upon reference to the accompanying description when taken in conjunction with the following drawings, wherein—

Figure 1 is a perspective view of the operating room lamp of this invention looking upwardly at the lamp;

Figure 2 is a top view of the lamp and the supporting frame illustrated in Figure 1, with a portion of supporting arm removed for clarity;

Figure 3 is a side elevational view of the operating room lamp illustrated in Figure 1;

Figure 4 is a sectional view taken along the lines 4—4 of Figure 2 and in enlarged scale to show the details of the drive and the manner in which the frame is rotatably supported in the tubular casing; and

Figure 5 is a sectional view similar to that of Figure 4 but showing a modification wherein the compensating spring is separate from the screw shaft adjusting drive.

The present invention essentially comprises a lamp mounted on one end of a supporting frame which is pivotally mounted in the manner of a lever on the lower end of a vertical supporting arm. A compensating spring is employed between the other end of the frame and vertical supporting arm to maintain the frame in a substantially horizontal position. The adjusting means for tilting the lamp is also mounted on the same side of the frame as the compensating spring. Thus it can be seen that the lamp may be adjusted on the opposite end of the frame

2

which is remote from the region where the operation is being performed.

Proceeding now to the drawings, more particularly to Figure 1, wherein like reference symbols indicate the same parts throughout the various views, 1 indicates generally the operating room lamp of this invention which is supported from a ceiling fixture 2. The lamp comprises a curved supporting arm 3 which has an upper horizontal portion 4 whose end is pivotally attached to the ceiling at 5 for rotation of the supporting arm about the vertical axis A—A. The lower end of the supporting arm is substantially vertical, as indicated at 6. A rotary member 7 is mounted within the lower end of the supporting arm and is free to pivot about the vertical axis B—B.

A tubular casing 8 comprises two axially spaced sections 9 and 10 which are joined together by a strap 11 and is pivotally supported at 12 on the rotatable member 7. Consequently, the tubular casing 8 is free to rotate about the horizontal axis C—C.

A shaft 13 is rotatably mounted within the tubular casing 8 for pivotal movement about a horizontal axis D—D which is at right angles to the horizontal axis C—C. A supporting frame comprising arms 14, which are attached to the rotatably mounted shaft 13 between the tubular casing sections 9 and 10, pivotally supports a lamp 15 which is free to pivot about a horizontal axis E—E. The lamp comprises a plurality of individual spotlights 16 which may be arranged in a circle and directed at a point. The lamp has a stainless steel horizontal handle 17 and a plurality of vertical handles 18. There is a vertical handle 19 attached to the rotatable shaft 13 between the sections of the tubular casing.

The drive means for the horizontal adjustment of the lamp frame is generally indicated at 20 and, as may be seen in Figure 3, comprises a threaded socket or tube 21 which is mounted in a tube 22 which, in turn, is pivotally mounted at 23 to a bracket 24 extending laterally from the rotatable member 7 in the supporting arm. A screw shaft 25 passes through a cross head 26 which is pivotally mounted in the tubular casing section 9 and is received within the threaded socket 21. The lower end of the screw shaft, which is not threaded, rotates within a bearing lining the interior surface of the cross-head. Collars on the unthreaded portion of the screw shaft on both sides of the cross-head restrict the screw shaft against axial movement.

There is a hand wheel 27 on the free end of the screw shaft 25 for rotating the shaft. A compensating spring 28 surrounds the screw shaft 25 and is received within the tube 22. A second tube 29 is telescopingly received within the tube 22 and the tubes 22 and 29 form an adjustable enclosure for the screw drive of the compensating spring. The length of these telescoping tubes is such that they will remain engaged regardless of the position of the lamp. It is apparent that the above-described drive means will also serve to prevent accidental tilting of the lamp frame under the influence of a force other than one which produces intentional actuation of the drive means, i.e., rotation of the hand wheel 27.

It is apparent that the weight of the lamp on the supporting frame would cause a torque moment and resultant pivoting of the supporting frame about the axis C—C. To overcome this moment the compensating spring is so chosen that in the average or normal position of the operating lamp, which is approximately the horizontal position, the spring neutralizes the torque moment generated by the operating lamp. Consequently, in this position the system is in balance. During the manipulation of the screw shaft by the hand wheel 27 the spring is either extended or compressed. Thus, one result of the spring arrangement is that less force need be exerted when

the drive means is being adjusted to vary the height of the lamp.

Since the supporting frame for the operating lamp is in most cases employed in a horizontal position or only at a very slight angle from the horizontal, the screw shaft drive as described above will be inclined with respect to the lamp frame. However, only the vertical components of the force as exerted by the screw shaft drive is effective for adjusting the position of the operating lamp. In order to minimize the forces exerted by the lamp and to obtain as great a vertical component force from the screw shaft drive as possible, the drive and the compensating spring are mounted at an angle of between 35° to 55° with the supporting arm vertical portion.

A modification of the spring and driving arrangement is illustrated in Figure 5. In this modification, the compensating spring is mounted separately from the drive means. The modification comprises a threaded tube 30 which has one end thereof pivotally mounted at 31 to the supporting arm vertical position. A screw shaft 32 is slidably mounted in a cross head 33 which is pivotally mounted in the tubular casing section 9. The threaded end of the shaft 32 is received within the threaded tube 30.

A compensating spring 34 is connected between the supporting arm vertical portion 6 in the tubular casing section 9. Telescoping tubes 35 and 36 completely enclose the compensating spring. Because of the length of the compensating spring a guide rod 37 is positioned within this spring. In operation, this modification is exactly similar to that of the invention as illustrated in Figure 4.

Thus it can be seen that the present invention provides an operating room lamp which may be readily adjusted about five different axes. The most important adjustment of the lamp which is the vertical height of the lamp is achieved by manipulating controls which are located remote from the area in which the operation is being performed.

In addition, the action of the compensating spring greatly decreases the amount of force which is necessary to adjust the height of the lamp. Since one end of the compensating spring is fastened to the tubular casing construction, the force of the spring does not act on the rotatable shaft from which the frame is supported and transmitted directly to the casing sections. The result is

a simplified construction for an operating room lamp which has a plurality of adjustments.

It will be understood that this invention is susceptible to modification in order to adapt it to different usages and conditions, and, accordingly, it is desired to comprehend such modifications within this invention as may fall within the scope of the appended claims.

What I claim is:

1. In an operating room lamp, a supporting arm with the upper portion thereof being substantially horizontal and the lower portion thereof being substantially vertical, means for mounting the horizontal portion of said supporting arm for pivotal movement around a vertical axis, a non-rotatable tubular casing comprising two rigidly connected axially spaced sections with one of said sections pivotally mounted on the end of said supporting arm vertical portion for pivotal movement around a first horizontal axis, a shaft rotatably mounted in both sections of said tubular casing for pivotal movement about a second horizontal axis, a frame secured to said rotatable shaft and extending on the side of said pivotal mounting opposite from said tubular casing, a lamp mounted on said frame, a handle on said rotatable shaft between said sections of the tubular casing for rotating said frame around said second horizontal axis, a threaded tube having one end pivotally mounted on the lower vertical portion of said supporting arm on the side toward said tubular casing, a screw shaft pivotally supported on the other of said sections and received within said threaded tube for tilting said frame about said first horizontal axis, a handle on one end of said screw shaft for rotating said shaft, a compression spring having one end engaging an element on said supporting arm vertical portion at a point spaced from said pivotal mounting and with the other end engaging said other section.
2. In an operating room lamp, as claimed in claim 1, with said compression spring surrounding said screw shaft.
